(57) **CLAIM**

The ornamental design for a magnetic resonance tomography diagnosis apparatus, as shown and described.

DESCRIPTION

FIG. 1 is a perspective view (1) of a magnetic resonance tomography diagnosis apparatus showing our new design; FIG. 2 is a perspective view (2) thereof; FIG. 3 is a rear perspective view thereof; FIG. 4 is a front elevational view thereof; FIG. 5 is a rear elevational view thereof; FIG. 6 is a top plan view thereof; FIG. 7 is a bottom plan view thereof; FIG. 8 is a left side elevational view thereof; FIG. 9 is a right side elevational view; FIG. 10 is a sectional view taken along line 10-10 with internal mechanism being omitted thereof; FIG. 11 is a sectional view taken along line 11-11 with internal mechanism being omitted thereof; FIG. 12 is an enlarged view of the part partitioned by 12-12 thereof; and, FIG. 13 is an enlarged view of the part partitioned by 13-13 thereof.

The dash-dot lines and the broken lines immediately adjacent the shaded areas represent the bounds of the claim, while all other broken lines are directed to environment and are for illustrative purposes only. The broken lines form no part of the claimed design.
